US0D1070758S

(12) **United States Design Patent** (10) **Patent No.:** **US D1,070,758 S**
(45) **Date of Patent:** ** *Apr. 15, 2025

(54) **WIRELESS CHARGER**

(71) Applicant: **Anker Innovations Technology Co., Ltd.**, Changsha (CN)

(72) Inventor: **Weifeng Luo**, Shenzhen (CN)

(73) Assignee: **Anker Innovations Technology Co., Ltd.**, Changsha (CN)

(*) Notice: This patent is subject to a terminal disclaimer.

(**) Term: **15 Years**

(21) Appl. No.: **29/939,486**

(22) Filed: **Apr. 26, 2024**

(51) LOC (15) Cl. **13-02**

(52) U.S. Cl.

USPC **D13/108**

(57) **CLAIM**

The ornamental design for a wireless charger as shown and described.

DESCRIPTION

FIG. 1 is a front top perspective view of a wireless charger showing my new design;

FIG. 2 is a rear bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the wireless charger that form no part of the claimed design.

1 Claim, 8 Drawing Sheets
